**METHOD AND APPARATUS FOR REMOVING
A PIPE FROM THE WELL**

Rural W. Whann, 315 W. 9th St., Los Angeles, Calif.

Filed Sept. 20, 1960, Ser. No. 57,873

11 Claims. (Cl. 166—35)

This invention relates to a tool for use in separating a string of pipe in a well above the point at which the pipe is stuck. This application is a continuation-in-part of my copending application entitled Method and Apparatus for Removing a Pipe From the Well, Serial Number 363,334, filed June 22, 1953, now abandoned.

When a string of pipe becomes stuck in a well and it becomes necessary to remove at least a portion of the pipe, an operator must determine the location of the highest point at which the pipe is stuck if he is to remove as much of the pipe as possible. When an operator employs a tool of well-known type for locating the point at which a pipe is stuck in a well, he thereafter removes the locating tool from the well and employs another tool for separating the pipe above its stuck point. In the time consumed by these operations of withdrawing the locating tool from the well and positioning a pipe separating tool down in the well, the pipe may become stuck or frozen at a point above that which has been located, whereupon the operator will have to determine the location of the new stuck point. Thus, he not only loses benefit of the time and effort he has already spent, but also he may not be able to salvage or reclaim that portion of the string of pipe lying below the highest stuck point. This chance that the pipe may become stuck or frozen at a higher point is especially great during drilling operation, for, when drilling has been stopped for any reason, the drilling mud used in the drilling operations may gel or thicken around the stationary drill stem, or a freshly penetrated earth formation may be caused to cave in on the drill stem. It is important therefore, that no time be lost in separating a drill stem above its stuck point and removing it from the well. It is important, too, that the pipe separating tool be positioned adjacent to a point in the pipe which is known to be free, i.e. above the highest stuck point, when the pipe is being separated, in order to insure that the portion of the pipe above the place of separation thereof may be pulled from the well and not be found to be stuck at a higher point after it has been separated. As used herein the word "pipe" refers to a drill stem, a string of casing, a tubing or any other string of pipe employed in a well.

The present invention makes it possible to separate a pipe in a well at a point thereof which is known to be free at the time of separation, and it is an object of this invention to provide a tool that not only locates the highest stuck point and permits an operator to separate the pipe immediately above that point in but a single trip of the tool into the well, but also transmits a signal or indication to the top of the well that the tool is positioned adjacent to a free point in the pipe when the pipe is being separated with use of the tool.

It is a further object of the present invention to provide a well tool that may be positioned at a free point in the pipe immediately above its highest stuck point in a simple and quick operation.

A still further object of the invention is to provide a well tool that operates quickly and effectively in separating a stuck pipe at a known free point thereof.

Another object of the invention is to provide pipe separating means that is simple in construction and adapted for use in combination with most any of the types of stuck point locating tools that are used in well operations.

There are several known methods for separating a pipe

2

at a point down in a well. A pipe may be severed as, for example, by being shot off or cut off with the use of a jet cut off tool, or the pipe may be backed off by twisting it in a direction that will unscrew a threaded joint thereof which connects two sections of the pipe. In the backing off method of separating a pipe, it is necessary first to jar or otherwise loosen a threaded connection of the pipe, before the pipe can be unscrewed at that connection. When the pipe connections are formed of collars around adjacent ends of the pipe sections, an operator may jar the collar at the connection to be separated, and in some cases expand the collar, in order to loosen it. In one form of the present invention I provide a well tool having means for finding a pipe connection in the free portion of a pipe above the highest point at which the pipe is stuck in a well, such pipe connection finding means being positioned on the tool within the limits of means for jarring the located connection, whereby, upon signal that the position of the desired pipe connection has been located, the said jarring means will be positioned directly opposite to such pipe connection and the connection may be loosened without further adjustment of the tool in the well.

It is another object of this invention to provide a stuck point locating tool that operates in response to torque applied to the top of the pipe, and having connection jarring means, whereby the impact of the jarring force loosens a known free pipe connection while torque is being applied in a direction tending to unscrew the connection, thus causing the pipe to spin loose when the jarring force is released.

It is another object of the invention to provide a stuck point locating tool which carries an explosive separating charge at a position on the tool corresponding to the position at which it is desired to separate the pipe when the stuck point is found.

Another object of the invention is to provide a method involving determining the lowest free point of a pipe in a well or bore hole and simultaneously positioning an explosive charge adjacent the free point whereby the separation of the pipe can be effected by means of the same tool or instrumentality without further movement thereof after the free point has been found.

It is still another object of the invention to provide a locating tool to locate the first free pipe collar above the stuck point and carry a jarring charge to this point whereby the charge is separated from the locating tool and fixed in the threaded collar joint so that the locating tool may be moved to a safe distance above the explosive charge thereby saving the locating tool.

Another object of the invention is to provide for a continuous and progressive operation in which time is reduced and the economy of the operation is raised.

Further objects and advantages of the invention will become apparent from the following detailed description taken in connection with the drawings, which are for illustrative purposes only, wherein:

FIG. 1 is a schematic sectional view showing a pipe which is stuck in a well, with an embodiment of the invention positioned therein and shown in elevation with a portion thereof shown in vertical section;

FIG. 2 is a vertical section of the lower portion of an alternative form of the invention;

FIG. 3 is a vertical section of a portion of another alternate form of the invention;

FIG. 4 is another alternative form of the invention showing a side elevation with a portion broken away in which the spring fingers are in a locked inoperative position;

FIG. 5 is a similar view to FIG. 4 but the spring fingers are shown in a released position;

FIG. 6 is a vertical section of the arrangement shown in FIG. 5; and

FIG. 7 is a sectional view taken on line 7—7 of FIG. 6.

Throughout the drawings, like reference numerals represent like parts throughout the several illustrated embodiments.

For purposes of simplifying the description hereof, I have chosen to describe the present invention by reference to the torsion sensing tool illustrated and described in U.S. Letters Patent No. 2,550,964, granted on May 1, 1951 to Norman Brookes. Referring to FIG. 1 of the drawing hereof, the numeral 10 designates a string of pipe which is stuck in a well 11 at 12. The well tool 15 which I have shown positioned in the pipe 10 is similar in certain parts thereof to the tool shown in the said Patent No. 2,550,964, and which operates in response to torque applied to the top of the pipe at ground level. The tool 15 comprises a pair of pipe engaging members or bow spring cages 16 and 17, spaced apart by the bar 18. The upper cage 16 is rotatably mounted on the bar 18 while the lower cage 17 is fixed to the bar.

The tool 15 is lowered into the pipe 10 by means of the cable 19 which is secured into the cable socket 20 mounted on and rotatable with the top end of upper cage 16. The cable socket 20 contains certain electrical elements that are arranged in a known way so as to be actuated in response to relative rotation of the cage 16 and the bar 18. Such electrical elements are connected through conductors inside the cable 19 to electro-responsive indication means at the top of the well, whereby any electrical impulses caused by such electrical elements as a result of relative rotation of cage 16 and bar 18, will be indicated to the operator at the top of the well. The details of construction and mode of operation of such electrical elements, electro-responsive indication means and the circuit therefor, do not constitute the essence of the present invention, and it is considered sufficient for the purposes of this description to refer to such elements and means, generally, as those not familiar with the details thereof may refer to the said Patent No. 2,550,964, for a full and complete description.

In the embodiment shown in FIG. 1, a pipe severing means, designated generally by the numeral 25, is mounted on the bar 18 at a location between the cages 16 and 17. The pipe severing means which is illustrated comprises a shaped charge of explosive material 26 having sufficient explosive capacity to cut the pipe 10 off at that portion thereof which surrounds the shaped charge. The shaped charge of explosive material 26 is supported between two discs 27 and 28, threaded on opposite ends of a sleeve 29 secured to the bar 18 as with the screws 30. A covering 31, of paper or other suitable substance, protects the explosive material from being damaged. A detonation or blasting cap 32 is fitted into a well in the shaped charge through a slot 33 in the disc 27 and is electrically connected to the conductors 34 which in turn are connected to a suitable blasting box 35 at the top of the well. The wires or conductors 34 may be attached to the bar 18 as with clips 36 or other suitable tying means, and, as is obvious, they may, if desired, be contained within the cable 19.

In operation, the tool is lowered into the pipe 10 and torque is applied to twist the pipe, whereby only the free portion thereof, i.e., that portion above the highest stuck point 12, will be turned while that portion of the pipe below the stuck point will not turn. Upon applying torque to the pipe relative rotation occurs between adjacent annular portions of the pipe throughout its full length above the stuck point. If at the time of applying such torque, the stuck point locating and pipe severing tool is positioned above the stuck point 12, the angle of rotation of the upper cage 16 will be greater than that of the cage 17 and bar 18. This occurrence of relative rotation between the elements of the tool will be transmitted by the electrical elements and electro-responsive indication means

to the top of the well, and the operator will know that his tool is positioned above the highest point at which the pipe is stuck. The operator will then further lower the tool and again twist the pipe, repeating these steps until a position is reached where no rotation of the tool occurs. When no relative rotation between the cages of the tool has occurred upon twisting of the pipe, the electro-responsive indication means at the top of the well will be still and the operator thus knows that his tool is located below the stuck point. He thereupon raises the tool to a location where relative rotation occurs and preferably while torque is still applied to the pipe, he operates the blasting box 35 causing the shaped charge 26 to explode and sever the pipe at the annular portion surrounding the explosive, which portion is known to be free at the time of the explosion. Instead of locating the stuck point by making tests at successively lower points in the free portion of the pipe, the operator may lower the tool to the bottom of the well and make his tests at successively higher points until he reaches a position where relative rotation occurs between the elements of his tool, whereupon he may cut the pipe off at that position in the manner described above. By maintaining a twist on the pipe and operating the pipe separating means only upon indication of relative rotation between the pipe engaging members, the operator will know that the pipe is being cut off at a point above its highest stuck point, and he may proceed to raise the pipe immediately without fear that it has become stuck above the place of cut off.

In the modification shown in FIG. 2, I provide a means for jarring a pipe connection in the free portion of the pipe, and means for finding such connection, the connection finding means being arranged within the limits of the jarring means on the well tool, whereby upon location of a pipe connection above the point at which the pipe is stuck, the jarring means will be positioned opposite to such pipe connection without further adjustment of the tool. The connection jarring means in the illustrated embodiment includes the rod 40 which is suspended by the cup 41 from the lower end of the bar member 18 below the pipe engaging member 17. The cup 41 is fastened to the end of the bar member 18 in any suitable manner, as by the screws 42. Wound around the rod 40 and extending the full length thereof is a string 43 of explosive material, such as, for example, primacord. One end of the explosive cord 43 extends into the cup 41 and is knotted around a detonation or blasting cap 44 wired to a blasting box at the top of the well.

The connection finding means of the embodiment shown in FIG. 2 comprises a tubular member 45 having a plurality of springs 46 circumferentially secured thereto. The rod 40 passes through the tubular member 45 and thereby supports the connection finding means. Axial movement of the tubular member 45 with respect to the rod 40 is prevented by means of the screws 47. The springs 46 extend outwardly and upwardly from the tubular member 45 and are formed so as to normally extend outwardly beyond the circumference of the well pipe. In FIG. 2, the string of pipe 10 is shown as comprising an upper section 50 and a lower section 51, the adjacent ends of the sections being connected by means of a threaded collar 53. In practice, the pipe sections do not abut each other, thus leaving a space 54 between the ends of the pipe sections. The springs 46 are shown in the drawing as being engaged with the shoulder 55 provided by the end of pipe section 50 in the space 54 between the pipe sections.

In operation the tool shown in FIG. 2 is lowered into the well and as explained above for operating the tool shown in FIG. 1, the pipe is tested at successively lower points until the stuck point is located. The tool is then raised to a position indicating relative rotation between the bow spring cages. With torque applied to the pipe

in a direction tending to unscrew the connection 53, the tool is again raised until the springs 46 snap into the space 54 of the pipe connection and engage the shoulder 55. This action of the springs 46 offers strong resistance to further upward movement of the tool in the well thereby signalling the operator that a pipe connection has been located in the free portion of the pipe. Thus, the explosive cord 43 becomes positioned centrally of the pipe connection and upon detonation thereof, it imparts a severe shock to the pipe connection and with the twist that is being applied at the top of the well, causes the pipe to spin loose at that connection.

In FIG. 3, the connection finding means and the string of explosive material are shown as being positioned between the two pipe engaging members 16 and 17. The sleeve member 58, which corresponds in function and design to the tubular member 45 shown in FIG. 2, is secured to the bar 18 in any suitable manner as with the screws 59. The string or cord of explosive material 60 is wound around the bar 18 and the sleeve member 58 and is secured to the bar 18 in any suitable fashion as with the clip 61. As in FIG. 2, the explosive cord is provided at its upper end with a detonation or blasting cap 63, electrically connected to a blasting box at the top of the well. The arrangement shown in FIG. 3 positions the explosive string centrally of the free pipe collar to be jarred upon location of such collar above the point at which the pipe is stuck. The explosive string extends beyond the limits of the collar finding means and is preferably actuated while the collar is being strained by a force tending to unscrew it from the top of the well. It seems obvious, therefore, that the use of a tool of the type hereinabove described will insure the operator thereof that the pipe connection jarring means is positioned opposite to a pipe collar which is known to be free and above the highest stuck point of the pipe when the jarring means is actuated.

If desired, the explosive charge for cutting off the well pipe may be positioned on a rod secured to the lower end of the bar 18, in a manner corresponding to that illustrated in FIG. 2. Also, it is obvious that the shaped charge 26 may be constituted of less explosive material than required for severing a pipe, whereby it acts to merely jar a threaded pipe connection. In the case where the collar jarring means comprises a shaped charge, as distinguished from a string or cord of explosive material, the pipe connection engaging ends of the connection finding springs are arranged to engage a pipe connection within the vertical limits of the shaped charge, whereby, upon location of a free pipe connection, the jarring means will be positioned directly opposite to such pipe connection without further adjustment of the tool in the well. It is obvious, too, that a pipe severing means or a connection jarring means, as herein described, may be positioned, if desired, on the cable 19 above the stuck point locating means of the tool.

From the foregoing it will be observed that in the form of the invention of FIG. 1, when the stuck point has been found, the explosive charge will at that time be positioned just above it in proper position for separating the casing. No further movement of the tool is required, and accordingly, substantial economies in time and manipulation of equipment are achieved. In the forms of the invention shown in FIGS. 2 and 3, after the stuck point has been found, there is only one further movement of the tool, that is, to the first collar above the stuck point. The pipe can then be separated at that collar without further movement of the tool. Similarly, the time and number of manipulations involved are reduced.

In another modification shown in FIGS. 4 to 7, I provide a means for selectively finding a pipe connection above the point at which the pipe is stuck. The connection finding means, generally indicated at 70, comprises a tubular member 72 which is secured to the lower end of the bar 18 by a shear pin 74. The shear pin 74 is re-

ceived in aligned openings 76 and 78 in members 72 and 18 respectively. At the lower end of the tubular member 72 there is welded or secured in like manner a cup-like receptacle 80 having a bottom 82 and an annular wall 84 projecting upwardly from the circumferential edge of the bottom wall 82. The tubular member 72 is centrally located on the bottom wall 82 so as to form an annular cavity 86 between the inner side of the wall 84 and the lower end 88 of the tubular member 72. The annular cavity 86 receives the explosive jarring charge 90. A detonation or blasting cap 91 is fixed within the jarring charge 90 through an opening 101 in the locking plate 96 whereby the plate 96 acts in conjunction with the cup 80 as a support means for the explosive charge 90.

Electrical conductors 93 leading from the cap 91 are wrapped sufficiently around the tubular sleeve 72 so that the well tool may be separated from the charge 90 and moved upwardly in the pipe at a safe distance from the explosion.

There are a plurality of equally spaced spring fingers 92 circumferentially secured to the side wall 84. At the upper ends of the springs 92 there are lip portions 94 which, when in a locked position as shown in FIG. 4, are secured to the locking plate 96. The locking plate 96 has equally spaced peripheral projections 100 with slots or openings 102 to receive the lip 94 of the spring finger 92. Also shown in FIG. 6 is an actuating means 104 centrally located in the tubular sleeves 72 and shown as a solenoid having an armature 106 secured to the locking plate 96 so as to longitudinally move the plate 96 out of engagement with the spring fingers 92 causing the fingers to spread and extend into the space 54 between the ends of the pipe sections 52 and 51 respectively. In order for the plate 96 to slidably move on the sleeve 72, there have been formed vertical slots 108 in the lower end 88 of the sleeve member 72 to accommodate matching webs 110 which are in the locking plate 96. The solenoid 104 is electrically connected by the conductors 111 which in turn are connected to conductors 112 centrally mounted within the well tool bar 18 passing through the tool 15 and inside the cable 19 to the top of the well whereby an electrical impulse may be given at the desired time for releasing the spring fingers 92.

When it is desired to separate a pipe above the stuck point in a well, such as the first collar connection above the stuck point, the selective joint connection finding means is attached to the lower end of the well tool 15 by the shear pin 74. The combination of the tool is then lowered into the well pipe 10 and the sensing device then locates the first free collar joint above the stuck point in the well. The tool is then gradually lifted in an upward direction and in so doing, the solenoid is energized releasing the spring fingers 92 so they may engage in the space 54 between the upper pipe 52 and the lower pipe 51.

The fingers 92 will then engage the lower edge of the upper pipe 52, the spring fingers being of such a tension as to hold the jarring charge in place and force the shearing pin to shear at the lower end of the well tool and thereby leaving the connecting finding means located in a central position at the collar connection, that is, at the plane of the space 54 between the adjacent ends of the pipes at the selected joint. The well tool continues in an upward direction unwinding the conductor 93 of the detonation cap 91 to a sufficient length to clear the well tool from the explosion area of the jarring charge. Although I have shown a solenoid for releasing the locking plate 96, it can be well understood that the releasing means may be also a mechanical means. Likewise, it can be understood that the detonation cap may also be set off either by a mechanical means or by having the separated well tool taken from the well and thereafter dropping a weight or a go devil to set off the detonation.

Although the present invention has been illustrated and described with particular reference to a tool having bow spring cages for engaging the inner wall of the pipe, and

operating in response to torsional strain applied to the pipe, the pipe separating means of the present invention may be used in combination with other means for locating a point at which a pipe is stuck in a well. An example of such other stuck point locating means is illustrated and described in U.S. Patent No. 2,530,309, granted on November 14, 1950, to Philip W. Martin. Also, I desire to have it understood that other connection finding means may be used instead of the springs 46, such as, for example, any magnetic collar finder, the design and mode of operation of which are known to those skilled in the art of well tools; the essence of the present invention being the provision of a free point locating tool having means for causing a pipe to be separated at a place therein which is known to be free and above the highest point at which the pipe is stuck, when separation is effected.

I claim:

1. A method for separating a stuck pipe above a stuck point so as to salvage the free pipe, all in such continuous and rapid progression as to produce a substantially continuous unity of operation which comprises the steps of: inserting a combination stuck point measuring tool and explosive device; locating the stuck point of the pipe; determining the position of the first free collar joint above the stuck point; positioning an explosive jarring charge at the said joint, whereby the said charge may be released to engage said collar joint; holding said positioned charge in place with respect to the pipe; separating the measuring tool from said positioned charge and moving said tool to a safe area above the charge; and discharging said explosive.

2. A method for separating well casings above a stuck point so as to salvage the freed well casing, all in such continuous and rapid progression as to produce a substantially continuous unity of operation which comprises the steps of: inserting a combination stuck point locating and explosive device; locating the stuck point of the pipe; locating said explosive device at a desired free point relative to said stuck point; engaging the explosive device with the pipe at said desired point; separating the locating device from the explosive device; moving said locating device to a safe area in the casing; and discharging the explosive of said explosive device.

3. Apparatus for locating the stuck point of pipe in a well, locating explosive at a joint adjacent thereto, and igniting same to free the joint, the combination including: stuck point locator means adapted to be lowered into a well, including means whereby the stuck point of a pipe may be located, and including means at the surface of the well indicating where such stuck point is located; explosive means carried by the apparatus lowered into the well; means whereby said explosive means may be positioned adjacent to a joint in said pipe; there being means, whereby said explosive means is held in position; means permitting said explosive means to be separated from the remainder of the apparatus lowered into the well; and means at the surface of the ground whereby said explosive may be ignited.

4. Apparatus for locating the stuck point of a pipe in a well, locating explosive at a joint adjacent thereto, and igniting same to free the joint, the combination including: stuck point locator means adapted to be lowered into a well, including means whereby the stuck point of a pipe may be located, and including means at the surface of the well indicating where such stuck point is located; explosive means carried by the apparatus lowered into the well; means whereby said explosive means may be positioned adjacent to a joint in said pipe; means on said explosive means to engage said pipe; means permitting said explosive means to be separated from the remainder of the apparatus lowered into the well; and means at the surface of the well operable to fire said explosive means while the apparatus is still in the well.

5. Apparatus for locating the stuck point of pipe in a well, locating explosive at a joint adjacent thereto, and

igniting same to free the joint, the combination including: stuck point locator means adapted to be lowered into a well, including means whereby the stuck point of a pipe may be located, and including means at the surface of the well indicating where such stuck point is located; explosive means carried by the apparatus lowered into the well; means for holding said explosive means in a desired position on said pipe; means permitting said explosive means to be separated from the remainder of the apparatus lowered into the well; and means operable after the stuck point of said pipe is located for moving said explosive means to a joint above said stuck point.

6. A method of locating the stuck point of a pipe in a well and for promptly removing the free part of said pipe, said method including the steps of lowering into a well an instrument having stuck point determining means and an explosive, using said instrument to determine the stuck point of said pipe, locating the explosive at a desired position relative to said stuck point and securing said explosive to said pipe at said desired position, separating the stuck point indication means of said tool from said explosive, and igniting said explosive while said tool is still in said well.

7. An apparatus for salvaging pipe or casing from a bore hole comprising: a stuck point indicating device adapted to be lowered into the bore hole and having associated therewith surface apparatus by which the stuck point of the pipe is indicated; an explosive carried by said well tool; means for locating said explosive at a joint adjacent the stuck point of said pipe and for securing it to said pipe, said explosive and other parts of the well tool being separable from each other whereby said means for locating the stuck point may be removed from said explosive; and means operable from the surface of the ground whereby said explosive may be ignited without removing said indicating device from the well.

8. In a device for facilitating the selection and separation of a pipe at a collar connection comprising: a tubular member for attachment of means for lowering said device into a pipe string; a cup-shaped receptacle fixed to the lower end of said tubular member; an explosive jarring charge mounted in said receptacle; a plurality of spring fingers fixed on the outer peripheral wall of said receptacle; a locking plate mounted for longitudinal movement on said tubular member for locking said spring fingers in an inoperative position, said locking plate having equally spaced peripheral projections, said projections having openings to receive said spring fingers; and an electrically operated means for moving said locking plate out of engagement with said fingers whereby said fingers may engage in the collar joint of the pipe to be separated.

9. In a device for facilitating the selection and separation of a pipe at a collar connection, comprising: a tubular member having at its upper end an opening to receive means for lowering said device into a well, the lower end of said tubular member having a plurality of vertical slots; a cup-shaped receptacle fixed to the lower end of said tubular member; an explosive jarring charge mounted in said receptacle; a plurality of spring fingers fixed on the outer peripheral wall of said receptacle; a locking plate mounted for longitudinal movement on said tubular member for locking said spring fingers in an inoperative position, said locking plate having matching webs centrally located therein which are longitudinally moved in said slots in the lower portion of said tubular member, and equally spaced peripheral projections with slots to accommodate said spring fingers in an inoperative position; and an electrical means for moving said locking plate to an unlocked position whereby said spring fingers may engage a selected collar connection in said pipe string.

10. In a device for facilitating the selection and separation of a pipe at a collar connection, comprising: a tubular member for lowering said device into a pipe string; a cup-shaped receptacle fixed to the lower end of said tubular member; an explosive jarring charge mounted in

said receptacle; a plurality of spring fingers fixed on the outer peripheral wall of said receptacle; a locking plate mounted for longitudinal movement on said tubular member for locking said fingers in an inoperative position, said locking plate having equally spaced peripheral projections, said projections having openings to receive said spring fingers; and remote control means for moving said lock plate out of engagement with said fingers whereby said fingers may engage in the selection of a collar joint of the pipe to be separated.

11. A method for separating a stuck pipe in a well above a stuck point so as to salvage the free pipe, all in such a continuous and rapid progression as to produce substantially continuous unity of operation which comprises the steps of: inserting and lowering a tool for locating a stuck point in a well in combination with an explosive charge; locating the stuck point of the pipe; determining the position of the first free collar joint above the stuck point; engaging an explosive jarring charge to the pipe at said joint; remotely controlled releasing of said charge for engagement with said first free collar connection; separating the measuring tool from said positioned charge and moving said tool to a safe area above the charge; and discharging said explosive whereby the free pipe may be separated at the desired point above the stuck point.
